United States Patent Office.

CHRISTIAN WOLF, OF DANVILLE, ILLINOIS.

Letters Patent No. 77,698, dated May 5, 1868.

IMPROVEMENT IN HORSE-COLLARS.

The Schedule referred to in these Letters Patent and making part of the same.

TO ALL WHOM IT MAY CONCERN:

Be it known that I, CHRISTIAN WOLF, of Danville, in the county of Vermillion, and in the State of Illinois, have invented certain new and useful Improvements in Horse-Collars; and do hereby declare that the following is a full, clear, and exact description thereof, reference being had to the accompanying drawings, and the letters of reference marked thereon.

In the annexed drawings, making a part of this specification, A A represent the sides of a collar, which are made entirely of wood, and in shape to exactly fit the neck and shoulders of a horse or other like animal, substantially as shown in the drawings. At the top and outside of the said pieces, or sides A A, I secure, by means of screws passing nearly through the wood of the collar, suitable metallic plates B B, provided with suitable loops or buckles at their upper extremity, through which a hames or collar-strap, C, may pass. The strap C may be fastened in the usual and ordinary manner, but I make it four double by passing through the loops, and thereby fasten the upper ends of the sides A of my collar together. Underneath the strap C, I secure a pad, D, so as to protect the top of the neck of the animal from galling or cutting by the said strap C. This pad is secured or held in place by means of a common leather loop, through which the strap C passes, and the edges thereof are kept from curling or rolling under, by means of small metallic hooks or catches, which are made pointed, and then pressed through the material of said pads, and then bent or doubled over.

The line-rings or loops represented by E, in the drawings, are inserted through the straps or metallic plates B, and screwed into the collar A, and thereby assist in securing said plate, as well as furnishing the required guide for the driving-reins.

F F represent metallic straps or plates, provided with suitable slots or loops, to which the hooks, links, or harness-tugs are attached in any convenient manner. Said straps F extend from the front of the inside of the collar A, and around the front thereof, and secured thereto by means of screws, which extend nearly through the wood of the collar, so as to not only fasten said plates that they cannot become loose, but strengthen the material and prevent its splitting. The staples which hold the hold-back rings are screwed through said plates, as is fully shown.

H H represent metallic straps, at the lower ends of the sides of the collar, of similar construction with the straps or plates B B, provided with suitable loops or buckles, in which the hames or collar-strap or fastening is secured. The straps H H are secured by screws, as the straps or plates B and F, or by nicely-finished bolts passing entirely through the material of the sides A A. For my hames or collar-fastening, I secure, in the loop of one side of the collar A on its strap H, a metallic flanged or grooved guide or plate, I, as shown in the drawings. Said guide is curved on its upper side, so as to correspond with the shape desired to give the lower end of the collar. Between the sides or flanges of the guide I, I pivot a small lever or pawl, j, which is provided with a lip or projection on its upper side to catch in the teeth of the plate or ratchet-bar K. The pawl j is also provided with a groove or notch across its lower side, over which is placed a bolt or rod, x, so that it may work out and in only as far as may be required to attach and detach the same to or from the ratchet K.

A small spring, h, is pivoted in front of the pawl j, one end resting against the back thereof to keep it in place, and the other end resting on a suitable pin across the guide I, as is shown.

K represents a metallic bar or plate, curved so as to correspond with the shape of the upper side of the guide I, and having a series of notches or teeth on its lower side, in which the lip of the pawl j catches, and thereby secures or fastens the collar to or on the animal.

Having thus fully described my invention, what I claim as new, and desire to secure by Letters Patent, is—

The arrangement of a wooden collar, A, having the straps or plates B, F, and H, rim-guide E, and hold-back rings secured to it, as described, with the ratchet-bar K, guide I, pawl j, and spring h, all the parts being constructed and used as and for the purpose specified.

In testimony that I claim the foregoing, I have hereunto set my hand, this 14th day of February, 1868.

CHRISTIAN WOLF.
